UNITED STATES PATENT OFFICE.

FRANCIS J. WAINDLE, OF CHICAGO, ILLINOIS.

GAME APPARATUS.

1,116,650.

Specification of Letters Patent.

Patented Nov. 10, 1914.

Application filed November 24, 1913. Serial No. 802,632.

To all whom it may concern:

Be it known that I, FRANCIS J. WAINDLE, a citizen of the United States, residing at Chicago, in the county of Cook and State of Illinois, have invented certain new and useful Improvements in Game Apparatus, of which the following is a specification.

The object of this invention is to provide a novel game comprising a suitable board 10 and a plurality of "men" adapted to be moved into different places and different relative positions on the board, the game requiring a certain degree of skill to play it and affording amusement and entertainment 15 to the players.

In the accompanying drawings Figure 1 is a top plan view of a game board forming part of an apparatus constructed in accordance with my invention. Figs 2 and 3 are 20 top plan views of two of the playing pieces or "men", said views showing one man from each of the two opposing series. Fig. 4 is a side or edge elevation of the man shown in Fig. 3 looking in the direction of the arrow 25 4.

The preferred form of my invention will be herein described, without any intention, however, of limiting the invention to the precise details and arrangement shown in 30 the drawings, except as specified in the appended claims.

The apparatus comprises a suitable base or board 5 on the upper face of which is provided a series of pairs of tracks, there 35 being in the present instance four such pairs, each leading inwardly from the middle of one edge of the board and terminating adjacent the center point of the board. The pairs of tracks thus form a plus sign. The individual 40 tracks of each pair are distinguished from each other by giving them different colors, designs, ornamentations, or other characteristics. The color scheme is preferable, and, although the particular colors used are not 45 essential, I prefer to have one track of each pair red and the other one black. These colors have been indicated in the drawings, in accordance with the color scheme of the draftsman's chart in the rules of practice 50 of the United States Patent Office. The reference number 6 is herein used to designate the red tracks and number 7 the black tracks. At the inner ends of the pairs of tracks is a central space 8 which may be left white. 55 The tracks 6 and 7 of each pair preferably lie parallelly alongside of each other. Dis-

posed symmetrically on opposite sides of each pair of tracks are two sets of triangular spaces 9 arranged with their bases toward the respective tracks. Preferably there 60 are ten of these spaces in each set, the spaces being arranged in three rows or tiers, 9^a, 9^b and 9^c. Six spaces in the first row 9^a extend along one edge of the track 6 or 7. Three spaces in the second row 9^b are located along 65 side the second, third and fourth spaces, respectively, of the base row 9^a, and the remaining space 9^c constitutes the third row and is positioned alongside the central space of the middle row 9^b. These spaces may be 70 left white, and the surface of the board which is not occupied either by the tracks 6, 7, central space 8, or triangles 9, may be given a suitable tint, so that the white spaces 8 and 9 will stand out prominently. It is 75 these white spaces on which the "men" are moved.

The men are arranged in two sets of twelve each, the tops of each set being given different colors, as red and black, like the 80 tracks 6, 7, to distinguish the sets from each other. In shape the men are all alike, and each consists of a block which is triangular in plan view and is of a size to fit any of the triangular spaces 9. The three sides of 85 each man have different colors, two sides being red and black, respectively, to correspond to the colors of the tracks, and the third side being of a different color, preferably white. Thus the men of one set will 90 have their tops and one of their sides black, and the men of the other set will have their tops and one of their sides red. In order that the three colors on the sides of the men may be readily visible from above them, 95 the upper edges of the sides are beveled, as clearly shown in Figs. 2 to 4, and the colors from the sides of the blocks are carried up onto these beveled portions.

At the start of the game one player takes 100 the twelve black men, that is to say, the men whose tops are colored black, and the other player takes the twelve red men. Each player divides his set of men up into four groups of three men each, each group being 105 placed upon the three outermost triangles of each series. These triangles are indicated by letters, *x* for the red men and *y* for the black men. The player having the black men uses the triangles or spaces on the side 110 adjacent to the black track and places the black side of his men facing the track. The

player having the red men arranges his men similarly with relation to the red track.

The object of the game is for each player to move all of his men into the central space 8 and at the same time to oppose or block the movement of his opponent's men. In advancing the men toward the central space 8 the players are entitled alternately to move one man at a time. A "move" may consist either of pushing a man either forward, backward, or sidewise, onto an adjacent space, or it may consist in turning a man on the same space so as to present a differently colored side toward the track. Under the rules of the game a man may be turned only toward the right. A man may either be transferred from one space to another, or he may be rotated, but both of these movements cannot be made at one "move" of the player. When any man occupies a position with his own color facing the track, then such man may be moved in any direction, either forward, backward, or sidewise. When either of the other two sides of a man faces the track the man may only be advanced toward the center of the board. All moves must be on straight lines either parallel with or at right angles to the adjacent track. A man may be rotated at any time desired. Before a man may be moved from one of the innermost triangles 9 into the central space 8, the man must be in position with his own color facing the track.

Under certain conditions a man of one set may be "killed" or retired by a man from the other set when the latter is moved into a certain relation to the former. When a man is thus retired the opposing player takes the man and places him in the corner 40 of the board at his left. All of the men which either player succeeds in getting into the central space 8 are placed upon the right-hand side of the owner of the men.

The conditions under which the men are killed or captured will now be described. Whenever an opponent's man occupies any space in the base row 9^a, with either his red or black side toward the track, if the opposing player can in one "move" cause one of his men to occupy a space in his base row 9^a directly opposite from the man mentioned, and with his side adjacent to the track corresponding in color to the facing color of the opponent's man, then the latter will be considered killed or captured and may be removed from the board. Although a man occupies one of the spaces in the base row 9^a, if he has his white side adjacent to the track, he is neutral and cannot be captured or retired. This can be done only when either the red or black face is adjacent to the track. Likewise if a man occupies either of the rows 9^b or 9^c, he cannot be retired. Whenever a player in one move, either to an adjacent space or by turning one of his men,

can place the man in position to kill or retire an opposing man, the player is obliged to so move. If he fails to notice the play and make the move, his man which could have been so moved will be forfeited to the 70 opponent. Where two or more men of the same player are in position to so capture an opponent's man, if the player fails to notice and make the move, his man nearest to the center will be forfeited. No man can 75 be used either for retiring or checking an opponent until the man has been advanced at least one space from his original position.

It will be noted that the order of colors on the sides of the red men, when turning the men to the right, is first red, second black, and third white. The order on the black men is first black, second red, and third white. Thus a man of either set may be 85 turned to present the color of an opposing man by one turn to the right.

When all of the men of either player have either been retired or have been moved into the central space 8, the game is at an end. The player who has then advanced the largest number of men into the central space 8 is considered the winner. In case these numbers are a tie, then the player who has captured the largest number of his opponent's men will be deemed the winner. The men remaining along the tracks after the final move by either opponent do not count in scoring.

It is obvious that various changes in shape and relation of parts can be made in the embodiment shown in the drawings without departing from the spirit and scope of the invention as defined in the appended claims.

I claim as my invention:

1. A game apparatus comprising a board having on one face four pairs of substantially parallel tracks extending inwardly toward the center of the board and arranged in the form of a plus sign, one track of each pair having one design or color, and the other track of each pair having a color or design different from the first, the board having a series of triangular spaces on opposite sides of each pair of tracks, and two sets of triangular shaped men adapted to move along said spaces, said two sets being distinguished from each other by color or design like those of the tracks, two sides of each of said men having colors or designs 115 the same as said tracks, and the third side of each man having a different color.

2. A game apparatus comprising a board having two tracks distinguished from each other by color or design, and having a series of spaces on opposite sides of the two tracks, and two sets of men adapted to be moved along said tracks from one space to another and adapted to be turned in one of the spaces, each man having sides of differ- 130

ent colors or designs, one of the sides being the same color or design as the adjacent track.

3. A game apparatus comprising a pair of substantially parallel tracks having distinguishing characteristics, two sets of spaces positioned at opposite sides of said pair of tracks, and two sets of men adapted to occupy said spaces, each of said men having a plurality of sides one of which has a characteristic similar to that of the adjacent track.

4. A game apparatus comprising a pair of tracks of different designs or colors, two sets of triangular spaces located adjacent to said tracks, and two sets of triangular shaped men adapted to occupy said spaces, the three sides of said men having different designs or colors, one of which is the same as the adjacent track.

5. A game apparatus comprising a pair of tracks having different characteristics, two series of spaces positioned adjacent to said tracks, and two sets of men adapted to occupy said spaces, each of said men having a plurality of sides of different characteristics.

6. A game apparatus comprising a plurality of converging pairs of tracks, one track of each pair having a certain characteristic and the other track of each pair hav-

ing a different characteristic, a set of spaces located adjacent to each track, and two distinguishable sets of men adapted to occupy said spaces, the men having a plurality of sides provided with different characteristics.

7. A game apparatus comprising a board provided on one face with a plurality of spaces, and sets of men to occupy said spaces, each man having a plurality of sides provided with different colors or designs, the upper corners of said sides being beveled and the colors or designs being extended onto the beveled portions.

8. A playing-piece for a game apparatus comprising a triangular block having different colors or designs on its three sides, the upper edges of said block being beveled away, and the colors or designs being extended onto said beveled portion.

9. A game board comprising a pair of tracks of different colors or designs, and two sets of men each having a plurality of sides, the top and one side of each set of men being the same color or design as the respective track.

In testimony whereof I affix my signature in presence of two witnesses.

FRANCIS J. WAINDLE.
